UNITED STATES PATENT OFFICE.

FREDERICK B. PHILBRICK, OF WEST NEWTON, MASSACHUSETTS, ASSIGNOR TO THE GAMEWELL COMPANY, OF NEWTON UPPER FALLS, MASSACHUSETTS, A CORPORATION OF MASSACHUSETTS.

COMBINED TELEGRAPH AND TELEPHONE SIGNALING SYSTEM.

Application filed December 4, 1924. Serial No. 753,883.

This invention relates to combined telegraph and telephone signaling systems and is particularly adapted for embodiment in so-called "emergency signaling systems" such, for example, as municipal fire alarm systems; in which one or more circuits are provided, each serially connecting a headquarters or main station and a plurality of sub-stations, some of which sub-stations are equipped with signal formulating mechanism—with or without succession and non-interference features (such, for example, as in a well-known type of fire alarm street box) and other of which sub-stations are equipped with mechanism for audibly and visibly manifesting alarms, such, for example, as the equipment ordinarily provided for such purposes at fire stations.

In such signaling systems, signals of primary importance are transmitted telegraphically, as by the formulation of code signals characterizing the various street boxes, the importance of which is such that they should be given right of way over all other signals. On the other hand, operating conditions frequently render it desirable to provide for conducting communication between sub-stations and the main station, or between one sub-station and another, as when the fire department officers have occasion to communicate from a street box with the firemen at some fire house, or to communicate with the main station for the purpose of summoning an ambulance, fuel wagon or other accessory equipment; as well as for the purpose of ascertaining the need of diverting fire fighting apparatus from one location to another—as when additional fires occur while all or a large portion of the fire fighting equipment of the community are engaged at some one fire.

It has also been found that when defects of any kind develop in such fire alarm circuits, it is very desirable that means shall be available whereby an inspector or repairman may communicate with headquarters over a fire alarm circuit and that, for such purpose, calls for telephonic communication may be sent over any circuit without thereby causing response of the alarm apparatus therein.

Because of the fact that persons who send calls over fire alarm circuits are usually

laboring under such a degree of excitement as to render it impracticable to rely upon them to exercise discrimination as to whether the circuit is already in use, it has been found to be essential that such circuits shall at all times be maintained in condition for the transmission of alarm signals and—in most cases—to provide so-called "non-interference and succession" mechanism whereby simultaneous or concurrent attempts to transmit alarm signals from two or more stations will result in complete and correct transmission of the signals of each of such stations without further action on the part of those using them. It is therefore important that means provided for making telephonic calls and conducting telephonic communication shall not so alter the condition of such alarm circuits as to impair their availability for alarm transmission or so as to functionally affect non-interference and succession mechanism or in any way delay intended alarm transmission.

It is an object of this invention to provide a signaling system in which the usual telegraph signaling instrumentalities will be supplemented by the provision of facilities for transmitting telephone call signals and for conducting telephonic communication without thereby at any time impairing the effectiveness of the system for alarm transmission.

It is a further object of this invention to provide such a system in which the telephonic calling and communicating facilities may be utilized without affecting the functional characteristics of non-interference and succession mechanism at street boxes or the non-interference and repeating mechanism provided between circuits at the main station, when such a system employs two or more circuits.

It is a further purpose of this invention to provide such a system in which facilities are provided for readily establishing telephonic communication between circuits without impairing or altering the functional relationship of such circuits as to telegraphic alarm signals.

It is a further object of this invention to provide such a system which embodies, for the accomplishment of the various telephonic calling and communication functions,

well-known forms of apparatus which are readily obtainable both for initial installation and for repairs and replacements.

In order to facilitate comprehension of this invention, an illustrative embodiment thereof is diagrammatically indicated in the accompanying drawing, in which like reference characters refer to similar parts.

That portion of the signaling system which is preferably located at the main station is enclosed by dotted line *a*, portions suitable for locating in fire stations are enclosed by dotted lines *b*, *b'* and portions significant of the apparatus at street boxes are indicated at *C*, *C'*.

In the diagrammatic representations of apparatus at street boxes, the signaling contacts 21 are arranged for functional actuation in response to rotation of the code wheel 22, subject to non-interference and succession control by mechanism (not shown) which mechanism is arranged for response to the electromagnet 23 in a manner well understood by those skilled in this art; together with the usual shunt switch 24, sounder 25 and calling key 26. A shunt switch may also be provided, in accordance with ordinary practice, whereby the sounder 25 and key 26 will be short-circuited while the door of the box is closed, and whereby such short-circuit will be interrupted when the door is open, affording access to said key. As such a switch forms no part of this invention, it is omitted from the drawing in the interest of clearness and simplicity of disclosure.

Such street boxes are diagrammatically shown as being serially connected in a normally closed circuit (hereinafter referred to as a "box circuit"), which circuit leads to the main station and there includes telegraphic signaling means comprising the electromagnet 27 of the repeating mechanism P, manifesting means such as the bell M and current supply mechanism such as the battery Q'. Although only two such boxes are shown in the accompanying illustration, it should be understood that any desired number of such boxes may be serially connected in such a circuit, and that additional box circuits may be similarly connected to the main station.

The repeating mechanism P may, for example, be of a type such as is shown and more fully described in Patent No. 810,912, dated January 30, 1906, which mechanism has circuit controlling means comprising the pens 30 and 31 and an insulated cylinder 32 which carries a contact plate 33 arranged so that, during normal positioning of said cylinder, said plate will be situated in contact with the free ends of said pens, and so that, during a portion of each rotation of said cylinder, said plate will be carried out of contact with said pens.

A second normally closed circuit (hereinafter referred to as a "fire station circuit") serially includes at the main station said pens 30 and 31 and plate 33, a current supply mechanism Q'' and a register R, and also includes at each of one or more fire stations, signal manifesting means such as the register R'. It should be understood that other fire station circuits may be similarly connected to said main station.

The telegraphic transmitter T and its associated transfer switch TS may be provided at the main station. Said transmitter may be of any well-known type which is suited for being manually set to transmit desired code signals, and is so associated with said transfer switch TS that the transmitter T may be connected in either of two box circuits to control the repeating mechanism therethrough, to the end that code signals may be transmitted therefrom through the repeating mechanism P to the fire station circuits. The signaling key 36 may be associated with the transmitter T as supplemental means for transmitting such code signals.

The battery Q' is arranged to apply an electromotive force to the box circuit supplied thereby which bears such relation to the normal resistance of said circuit as to assure normal current flow therethrough of not less than some predetermined intensity such, for example, as 100 milliamperes. The electromotive force of the battery Q'' is correspondingly adjusted with relation to the normal resistance of the fire station circuit supplied thereby, so as to cause correspondingly suitable normal current flow therethrough. The electromagnets of devices which should be responsive to the current flow incident to the formulation of telegraphic signals therein, such as the bell M, the repeating mechanism P and registers R and R', as well as the street box electromagnets 23, are arranged for effective energization upon current flow through the windings thereof which is, say, at least sixty per cent of the intended normal current flow in the circuit in which they are respectively included; and should be arranged for functional deenergization, following effective energization, whenever the current flow through the windings thereof is decreased to an intensity less than, say, twenty per cent of such normal current flow. Arrangement of such magnets so that effective energization thereof will occur at an intensity substantially less than that of the intended normal flow is provided for the purpose of affording a suitable factor of safety in accordance with ordinary practice in such systems; and the arrangement of such magnets whereby functional deenergization will occur prior to complete cessation of current flow through the windings thereof is correspondingly pro-

120
125
130

vided for the purpose of assuring response by the mechanism controlled by such magnets when an attempt is made to break the circuit at a point at each side of which there is sufficient leakage to permit slight current flow.

A signaling system comprising no more than the instrumentalities and arrangement thus far described would provide a typical 10 fire alarm system, the operation of which is well-known to those skilled in this art, and therefore will not be here described in further detail.

In applying this invention to the fire 15 alarm system just described, in the manner indicated by the accompanying drawing,— means is provided at each station for effecting telephonic communication over the circuit or circuits associated therewith. 20 Such means comprise call initiating and manifesting mechanism, telephonic transmitters and receivers and switching mechanism for bringing said transmitters and receivers in operative association with their 25 associated circuit. It will be noted that one or more portable telephone sets such as the set D, should be provided for use in connection with street boxes such as the boxes C, C'; each of which sets should include 30 means, such as the split plug 74, whereby such set may be connected in parallel with the current path through any box from which it is desired to establish telephonic communication.

35 The call initiating mechanism of each station comprises a normally closed current path of comparatively small resistance, in which path a calling key is provided for interrupting same when it is desired to initiate 40 a call; together with a resistance shunted around such path, which resistance is so proportioned to the resistance of the entire circuit with which it is used that, when the calling key is open, the current flow in such 45 circuit will be reduced from normal to an intensity such as will cause response of call manifesting mechanism, as hereinafter more fully explained, without so reducing such current flow as to cause functional deener- 50 gization of the electromagnets of devices which should be responsive to the current flow incident to the formulation of telegraphic signals. If it is desired to prevent interruption or mutilation of any tele- 55 graphic signal by the use of any calling key, each of such resistances should further be so proportioned to the resistance of the circuit in which it is included that, when the associated calling key is open, the cur- 60 rent flow in such circuit will not be so reduced as to prevent effective energization (after a break of the circuit) of any of such electromagnets.

At the street boxes C and C', the call 65 initiating mechanism shown comprises the

telephone set D and the key 26, as herein-after more fully explained; the call initiating means provided for each circuit at the main station comprises a resistance which is normally shunted by a closed circuit jack, as, 70 for example, the resistance 49' associated with the box circuit and normally shunted by the jack 67, together with a plug 69 so associated with a normally closed key 26' that, when said plug is inserted 75 in any one of said jacks and said key is thereupon opened, the current path of the circuit represented by such jack, will be interrupted, thereby rendering such resistance 80 effective for suitably diminishing the current flow in that circuit; and, in the fire stations B and B' the call initiating mechanism comprises resistances 49'', included in the associated circuit, which resistances are shunted by normally closed keys 26''. 85

In order to provide a suitable factor of safety, it is desirable that resistances forming part of call initiating mechanism, such as just described, shall be so proportioned to the normal resistance of the circuits with 90 which they are associated that the cycles of change in the intensity of current flow in such respective circuits incident to alternate breaking and closing of the shunt circuit around any one of such resistances will extend from a minimum which so exceeds the maximum of the cycles of change in intensity of current flow which constitute telegraphic signaling impulses, as to afford a 95 suitable factor of safety. For example, in a circuit wherein such telegraphic impulse cycles extend from a maximum of not less than sixty per cent to a minimum of not more than twenty per cent of normal current 100 flow, in order to assure corresponding cycles 105 of effective energization and functional de-energization of such magnets, a desirable factor of safety for telegraphic signals might be afforded by so proportioning resistances such as the resistances 49' and 49'' that, alternately breaking and closing the shunt 110 around any one of such resistances will cause cycles of change in intensity of current flow in the associated circuit, which cycles will extend from a minimum of not less than sev- 115 enty per cent of normal intensity.

The telephonic call manifesting mechanism provided at the various stations is arranged for response to cycles of change in the intensity of current flow from a maximum which may be somewhat below normal intensity to a minimum not greater than the minimum intensity of the cycles of change resultant from alternate breaking and closing of any one of the call initiating keys in 120 such circuit. In order to afford a factor of safety, it is desirable that such manifesting mechanism shall be responsive to cycles of 125 change of intensity in current flow which extend from a minimum somewhat in excess 130

- of the cycles of change which result from alternate breaking and closing of the shunt around any one of such resistances. For example, if the minimum current flow incident to such telephonic call cycles is seventy percent of normal intensity, such manifesting mechanism might be arranged to act in response to cycles extending from a minimum of not more than seventy-five per cent of normal. In the illustrative embodiment of this invention shown by the drawing, the telephonic call manifesting mechanism provided at the street boxes C, C' consists of the sounders 25, 25'; that at the main station comprises, for each box or fire station circuit, a relay (such as the relays 66 and 66') together with a lamp (such as the lamps 70 and 70'), relay 71 and buzzer 72 so associated therewith that, upon functional de- energization of any one of such relays, its associated lamp will be lighted, the relay 71 will be effectively energized and the buzzer 72 will sound; and, that at the fire stations B and B' comprises the sounders 25'', 25''.
25 The telephonic transmitters and receivers, together with the switching mechanism associated therewith at the various stations is so arranged that, while in use, each transmitter and receiver will be bridged across a resistance; the resistances bridged by transmitters being such that variations in the resistance of any such transmitter will not unduly affect the intensity of the telegraphic signaling current flow in the circuit with which it is associated; and the resistances bridged across such receivers having such inductance as to cause practically all alternating current of telephonic frequency to pass through the receiver. Thus in the telephone set D, provided for use in association with signal boxes such as the boxes C, C', a current path is provided from one side of the split plug 74, through the transmitter 75 and the receiver 76 in series, to the other side of said plug; a switch S being so connected that, when closed, it will short-circuit the transmitter 75 for a purpose which will be hereinafter more fully explained; at the main station A, the telephone transmitter 40 is supplied by the battery Q^{IV} acting through the primary of induction coil 59 and through the retardation coil 61, which retardation coil and battery are bridged by the condenser 60; and the receiver 41 is connected through the secondary of the induction coil 59 with contacts of the key L for operative association through condensers 62 either with the pair of plugs 63, 63' or the pair of plugs 63'', 63'', dependent upon the position of the key L. In the case of the box circuit, the open jack 64 is connected in parallel with the windings of the electro-magnet 27 of the repeater P, the relay 66 and the bell M associated with said circuit; and, in the instance of the fire station cir- cuit, the normally open jack 64' is connected in parallel with the relay 66' and register R associated with said circuit; to the end that insertion of any one of the plugs 63, 63' or 63'', 63'', in the jack 64 or the jack 64', during appropriate positioning of the key L, will establish operative association between the transmitter 40 and receiver 41 and the circuit of such jack 64 or 64', as the case may be; and, in the fire stations B and B', the transmitter 40' is connected in parallel with the resistance 50 and the receiver 41' is arranged for connection in parallel with the sounder 25'' when the switch S'' is in the position which it occupies when the receiver 41' has been removed from the automatic hook 42'. It will be noted that a switch S' is associated with the transmitter 40 and receiver 41 at the main station, for at times cutting the battery Q^{IV} off from the transmitter 40 and opening the circuit through the receiver 41, in accordance with ordinary practice.
- Normal current paths.*
- The normal current path through the box circuit shown, is as follows: from one side of the battery Q' through conductor 81, bell M, conductor 82, and a portion of the repeating mechanism P including one of the electromagnets 27, thence through conductor 83 to one terminal of street box C, thence through the key 26, sounder 25 and the telegraphic signaling mechanism comprising the magnet 23, contacts 21 and the shunt switch 24 to the other terminal of said box, thence through conductor 84 to and correspondingly through street box C' and any other boxes similarly connected in said circuit, and through conductor 85, to and through relay 66 to parallel current paths one of which includes the resistance 49' and the other of which includes the closed-circuit jack 67, thence through conductor 88 to the transfer switch TS and, when said switch is in the position shown, serially through the contacts of transmitter T and the key 36; thence through conductor 89 to the other side of battery Q'.
The normal current path through the fire station circuit, as shown, is as follows: from one side of the battery Q'' through conductor 90 and a portion of the repeating mechanism P including one pair of the pens 30 and 31 and their associated plate 33, thence through conductor 91 to and through the magnet winding of the sounder 25'' at the fire station B', to parallel current paths one of which includes the resistance 50, another of which includes the contacts 43 and 44 of the switch S'', and the other of which includes the transmitter 40', thence through register R' to parallel current paths one of which includes the resistance 49'' and the other of which includes the calling key 130.

26'', thence through conductor 100 to and correspondingly through the instruments at station B and any other similarly equipped stations in said circuit, and through conductor 101 to and through relay 66' to parallel current paths one of which includes the resistance 49' and the other of which includes the closed-circuit jack 67', thence through register R to the other side of the 10 battery Q''.

Operation.

If, when a signaling system such as that shown by the drawing is in normal condition, it is desired to establish telephonic communication from a street box such as the street boxes C, C', with the main station,—the split plug 74 of a telephone set such as the set D should be so inserted between the terminal plates of such box, as to connect said telephone set in parallel therewith, the switch S of such telephone set should then be manipulated so as to short-circuit the transmitter 75 while the calling 20 key 26 of such box is alternately opened and closed for a desired number of times. Each time said key is so opened, the resistance of the telephone receiver 76 will be effectively included in the circuit, thereby 25 serving to sufficiently diminish the current flow therethrough to cause the relay 66 to close the circuit through the lamp 70, thus lighting said lamp. The current flow incident to the lighting of the lamp 70, as just 30 described, will cause the relay 71 to establish a current path through the buzzer 72, as follows,—from one terminal of battery Q^{iv} to the armature and contact of relay 71, through buzzer 72, serially through normally closed contacts 106 and 107, and 35 108 and 109 of key L, to other side of battery Q^{iv}; thus causing said buzzer to sound. When the sounding of this buzzer has attracted the attention of the main station 40 operator, he will be enabled to answer the call by inserting one of the plugs 63, 63, or one of the plugs 63', 63', into the jack 64 and so operating the key L as to connect the plug so used with the operator's 45 telephone set comprising the transmitter 40 and the receiver 41. For example, if one of the plugs 63, 63 is so employed, the handle of the key L should be moved to the left, as shown by the drawing, thereby moving 50 the contacts 110 and 111 into engagement with the contacts 112 and 113, respectively, and, at the same time moving the contact 108 out of engagement with the contact 109, so as to interrupt the current path 55 through the buzzer 72. The operator may thereupon remove the receiver 41 from its associated automatic hook 42, thus permitting the contacts 53 and 55 to move into engagement with the contacts 54 and 56, 60 respectively. Upon engagement of the au-

tomatic hook contacts as just described, a current path will be established from one side of the battery Q^{iv}, through retardation coil 61, contacts 53 and 54, transmitter 40, and the primary winding of the induction coil 59, to the other side of said battery; and a telephonic current path will be established from one side of the one of the plugs 63 which is situated in the jack 64, through one of the condensers 62, through 70 contacts 112 and 110, through secondary of induction coil 59, through contacts 55 and 56, through receiver 41, through contacts 111 and 113, and through another of the condensers 62 to the other side of said 80 plug. From the foregoing it will be seen that the receiver 41 and the secondary of the induction coil 59 will now be connected in parallel with one of the electromagnets 27 of the repeating mechanism P, the bell 85 M, the battery Q', and the winding of relay 66 so that telephonic communication may be carried on between a person using the telephone set D at the street box from which the call originated and the operator 90 at the main station.

If, as a result of such conversation or otherwise, the operator at the main station desires to place such box circuit in communication with the fire station circuit,— 95 this can be accomplished by inserting the other of the plugs 63, 63 in the jack 64', inserting the plug 69 in the jack 67', and thereupon operating the calling key 26'. When such plug 63 is inserted in the jack 100 64', as just described, the telephonic circuit of the operator's set comprising the transmitter 40 and receiver 41, and the box circuit from which the call originated will 105 be connected in parallel, through certain of the condensers 62, with each other and with the relay 66', register R and battery Q'' of the fire station circuit. The condensers 62 are provided in such parallel 110 connections so as to permit currents of telephonic frequency to pass from one circuit to another without establishing any direct-current connection between such circuits or altering in any manner the functional relationship of such circuits as to telegraphic 115 signals. Upon each break of the calling key 26', while the plug 69 is in the jack 67', as just described, the shunt around the resistance 49' will be interrupted, thus causing diminution of current flow in the fire station circuit, as hereinbefore more fully explained. Upon such diminution of current flow in said circuit, the sounders 25'' of the stations B and B' will act, and the manipulation of the key 26' in accordance with some predetermined code may cause said sounders 25'' to manifest a signal which will be recognized as the specific call for one of such stations. In response 120 to such call, the receiver 41' at the station 125

so called may be removed from its hook 42', thereby permitting the contact 44 to move away from the contact 43 and the contact 45 to move into engagement with the contact 46; so as to break the shunt which had previously been effective between the contacts 43 and 44 around the transmitter 40', and to connect the receiver 41' in parallel with the sounder 25" at such station.

10 From the foregoing it will be apparent that, while conditions are as just described, conversation addressed to either the transmitter 40, the transmitter 40' or the transmitter 75 will be reproduced by the receivers 41, 41' and 76; and that, notwithstanding the conditioning of these circuits for telephonic communication, sufficient current flow will be maintained therein so that if the telegraphic transmitting mechanism of one of the boxes C, C' is set in motion, the bell M will respond to the signal of such box, and the repeating mechanism P will act in response thereto to cause manifestation of such signal by the register R at the main station and by the registers R', R' at fire stations B and B'. It will also be apparent that if, when it is desired to establish telephonic communication from one of the boxes C, C', a telegraphic signal is in course of transmission from another of such boxes or from the transmitter T at the central office, notice thereof will be given by the sounder 25 at such street box, so that the transmission of the telephonic call may be deferred until the completion of such telegraphic signal.

If any resistance which is, in effect, inserted in the line when initiating a telephonic call, is not so proportioned to the total normal resistance of the circuit as to avoid diminution of current flow below the intensity needed for the effective transmission and manifestation of telegraphic signals, as hereinbefore more fully explained, those who have occasion to send telephonic calls should be warned to observe the associated sounder 25 before attempting to send a telephonic call; and to defer sending such call if the sounder indicates that a telegraphic signal is in the course of transmission and, in any event, it is preferable that telephonic calls shall not be made when the associated sounder is acting, even if such action is in response to another telephonic call, in view of the fact that effective concurrent inclusion of two calling resistances in the same circuit might reduce current flow therein below that at which the transmission and manifestation of telegraphic signals is assured.

60 If it is desired to telephonically call the main station from one of the fire stations B, B', the calling key 26" at such station should be opened, thereby effectively including the resistance 49" at such station in the circuit leading therefrom to the main sta-

tion and causing response of the call manifesting relay 66" at the main station in a manner corresponding to that hereinbefore described in greater detail in connection with a call from one of the street boxes C, C'. Likewise, if it is desired to send a telephonic call from the main station to one of the street boxes C, C'—this may be accomplished by inserting the plug 69 in the jack 67, whereupon the sounders 25 may be caused to act. In this connection, it will be understood by those skilled in this art that if so-called "door shunts" are provided at the street boxes C, C', sounders in such boxes will act in response to such a call only at a box or boxes the door or doors of which are open.

It will further be obvious to those skilled in this art that, if desired, calling keys similar to the key 26" may be provided at the main station in place of jacks such as the jacks 67, 67' so that telephonic calls may be sent over any desired circuit without the use of a plug and jack; it will be correspondingly apparent that the number of street box circuits and fire station circuits may be increased at will, and that the system shown by the accompanying drawing and hereinbefore described in detail is merely illustrative of this invention; as various changes may be made in the construction and arrangement shown and described in detail without departing from the scope of this invention.

What I claim and desire to secure by Letters Patent of the United States of America is:

1. In a combined telegraph and telephone signaling system having main and sub-stations and circuits each serially connecting a respective one or more of said sub-stations with said main station and current supply mechanism arranged for normally causing suitable current flow in each of said circuits;—telegraphic signaling means comprising,—code signaling mechanism adapted for conditioning associated circuits to effect cycles of change between predetermined limits in the intensity of current flow therein, repeating mechanism at said main station having electromagnetic mechanism arranged for functional response to the aforesaid cycles of circuit condition and involving circuit controlling means arranged to formulate corresponding cycles in other of said circuits, manifesting means having electromagnetic mechanism arranged for functional response to such cycles of circuit condition, and non-interference mechanism responsive to the aforesaid cycles of circuit condition for controlling functional operation of said code signaling mechanism; and means for effecting telephonic communication over circuits between said stations comprising,—call manifesting mechanism arranged

- for functional response to cycles of change in the intensity of current flow in said respective circuits extending above the range of said first named cycles and during each 5 of which cycles such intensity is reduced to less than a predetermined value, said manifesting mechanism including means at said main station for indicating circuits in which calls originate, telephone instruments at said 10 main and sub-stations, said instruments at certain of said sub-stations including a telephone receiver of such resistance that the circuit associated therewith may be so conditioned by serially including said receiver 15 therein as to effect such second named cycles, together with means for so including any one of said receivers in an associated circuit and for operatively associating said instruments and circuits, means at other of said 20 stations for correspondingly conditioning the circuits respectively associated therewith, and means at said main station whereby said instruments thereat may be operatively associated with either or both of any 25 two of said circuits and whereby any two such circuits may be operatively associated with each other for telephonic communication therebetween, association of said telephone instruments with said circuits being 30 effected by so connecting respective ones of said instruments in shunt with windings of certain of said electromagnetic mechanisms as to maintain circuit conditions suited for complete intended functioning of said telegraphic signaling means and said call manifesting mechanism.
2. In a combined telegraph and telephone signaling system having main and sub-stations and circuits each serially connecting a 40 respective one or more of said sub-stations with said main station and current supply mechanism arranged for normally causing suitable current flow in each of said circuits;—telegraphic signaling means comprising,—code signaling mechanism adapted for conditioning associated circuits to effect cycles of change each involving not less than a certain predetermined reduction in the intensity of current flow therein, repeating 45 mechanism at said main station having electromagnetic mechanism arranged for functional response to the aforesaid cycles of circuit condition and involving circuit controlling means arranged to formulate corresponding cycles in other of said circuits, manifesting means having electromagnetic mechanism arranged for functional response to such cycles of circuit condition, and non-interference mechanism responsive to the 55 aforesaid cycles of circuit condition for controlling functional operation of said code signaling mechanism; and means for effecting telephonic communication over said circuits between said stations comprising,—call manifesting mechanism arranged for 60 functional response to cycles of change in the intensity of current flow in said respective circuits extending above the range of said first named cycles and during each of which cycles such intensity is reduced to less than a predetermined value, said manifesting 65 functional response to cycles of change each involving not less than a predetermined reduction in the intensity of current flow in said respective circuits which last named reduction is less extensive than said first 70 named reduction, said manifesting mechanism including means at said main station for indicating circuits in which calls originate, telephone instruments at said main and sub-stations, said instruments at certain of 75 said sub-stations including a telephone receiver of such resistance that the circuit associated therewith may be so conditioned by serially including said receiver therein as to effect such second named cycles, together with means for so including any one of said receivers in an associated circuit and for operatively associating said instruments and circuits, means at other of said stations for correspondingly conditioning the circuits 80 respectively associated therewith, and means at said main station whereby said instruments thereat may be operatively associated with either or both of any two of said circuits and whereby any two such circuits may be operatively associated with each other for telephonic communication therebetween, such association of said telephone instruments with said circuits being effected by so connecting respective ones of said instruments in shunt with windings of certain of 85 said electromagnetic mechanisms as to maintain circuit conditions suited for complete intended functioning of said telegraphic signaling means and said call manifesting mechanism.
3. In a combined telegraph and telephone signaling system having main and sub-stations and circuits each serially connecting a respective one or more of said sub-stations with said main station and current supply mechanism arranged for normally causing suitable current flow in each of said circuits;—telegraphic signaling means comprising,—devices having electromagnetic mechanism arranged for functional operation in response to cycles of change between predetermined limits in the intensity of current flow in one of said circuits thereat and mechanism for conditioning respective associated circuits to effect such cycles therein, said telegraphic signaling means including repeating mechanism at said main station responsive to such conditioning of certain of said circuits to cause corresponding conditioning of other of said circuits; and means for effecting telephonic communication over circuits between said stations comprising,—call manifesting mechanism arranged for 100 functional response to cycles of change in the intensity of current flow in said respective circuits extending above the range of said first named cycles and during each of which cycles such intensity is reduced to less than a predetermined value, said manifesting 105 mechanism.
4. In a combined telegraph and telephone signaling system having main and sub-stations and circuits each serially connecting a respective one or more of said sub-stations with said main station and current supply mechanism arranged for normally causing suitable current flow in each of said circuits;—telegraphic signaling means comprising,—devices having electromagnetic mechanism arranged for functional operation in response to cycles of change between predetermined limits in the intensity of current flow in one of said circuits thereat and mechanism for conditioning respective associated circuits to effect such cycles therein, said telegraphic signaling means including repeating mechanism at said main station responsive to such conditioning of certain of said circuits to cause corresponding conditioning of other of said circuits; and means for effecting telephonic communication over circuits between said stations comprising,—call manifesting mechanism arranged for 110 functional response to cycles of change in the intensity of current flow in said respective circuits extending above the range of said first named cycles and during each of which cycles such intensity is reduced to less than a predetermined value, said manifesting 115 mechanism.
5. In a combined telegraph and telephone signaling system having main and sub-stations and circuits each serially connecting a respective one or more of said sub-stations with said main station and current supply mechanism arranged for normally causing suitable current flow in each of said circuits;—telegraphic signaling means comprising,—devices having electromagnetic mechanism arranged for functional operation in response to cycles of change between predetermined limits in the intensity of current flow in one of said circuits thereat and mechanism for conditioning respective associated circuits to effect such cycles therein, said telegraphic signaling means including repeating mechanism at said main station responsive to such conditioning of certain of said circuits to cause corresponding conditioning of other of said circuits; and means for effecting telephonic communication over circuits between said stations comprising,—call manifesting mechanism arranged for 120 functional response to cycles of change in the intensity of current flow in said respective circuits extending above the range of said first named cycles and during each of which cycles such intensity is reduced to less than a predetermined value, said manifesting 125 mechanism.
6. In a combined telegraph and telephone signaling system having main and sub-stations and circuits each serially connecting a respective one or more of said sub-stations with said main station and current supply mechanism arranged for normally causing suitable current flow in each of said circuits;—telegraphic signaling means comprising,—devices having electromagnetic mechanism arranged for functional operation in response to cycles of change between predetermined limits in the intensity of current flow in one of said circuits thereat and mechanism for conditioning respective associated circuits to effect such cycles therein, said telegraphic signaling means including repeating mechanism at said main station responsive to such conditioning of certain of said circuits to cause corresponding conditioning of other of said circuits; and means for effecting telephonic communication over circuits between said stations comprising,—call manifesting mechanism arranged for 130 functional response to cycles of change in the intensity of current flow in said respective circuits extending above the range of said first named cycles and during each of which cycles such intensity is reduced to less than a predetermined value, said manifesting 135 mechanism.

mechanism including means at said main station for indicating circuits in which calls originate, telephone instruments at said main and sub-stations, means at said sub-stations for operatively associating said instruments and circuits, and means at said main station whereby said instruments thereat may be operatively associated with either or both of any two of said circuits and whereby any two such circuits may be operatively associated with each other for telephonic communication therebetween, association of said telephone instruments with said circuits being effected by so connecting respective ones of said instruments in shunt with windings of certain of said electromagnetic mechanisms as to maintain circuit conditions suited for complete intended functioning of said telegraphic signaling means and said call manifesting mechanism, and involving mechanism for so conditioning such circuits, respectively, as to effect such second named cycles therein.

4. In a combined telegraph and telephone signaling system having main and sub-stations and circuits each serially connecting a respective one or more of said sub-stations with said main station and current supply mechanism arranged for normally causing suitable current flow in each of said circuits; telegraphic signaling means comprising, devices having electromagnetic mechanism arranged for functional operation in response to cycles of change in the intensity of current flow in one of said circuits thereat each involving not less than a predetermined reduction in such intensity and mechanism for conditioning respective associated circuits to effect such cycles therein; said telegraphic signaling means including repeating mechanism at said main station responsive to such conditioning of certain of said circuits to cause corresponding conditioning of other of said circuits; and means for effecting telephonic communication over said circuits between said stations comprising, call manifesting mechanism arranged for functional response to cycles of change each involving not less than a predetermined reduction in the intensity of current flow in said respective circuits which last named reduction is less extensive than said first named reduction, said manifesting mechanism including means at said main station for indicating circuits in which calls originate, telephone instruments at said main and sub-stations, means at said sub-stations for operatively associating said instruments and circuits, and means at said main stations whereby said instruments thereat may be operatively associated with either or both of any two of said circuits and whereby any two such circuits may be operatively associated with each other for telephonic communication therebetween,

association of said telephone instruments with said circuits being effected by so connecting respective ones of said instruments in shunt with windings of certain of said electromagnetic mechanisms as to maintain circuit conditions suited for complete intended functioning of said telegraphic signaling means and said call manifesting mechanism, and involving mechanism for so conditioning such circuits, respectively, as to effect such second named cycles therein.

5. In a combined telegraph and telephone signaling system having main and sub-stations and circuits each serially connecting a respective one or more of said sub-stations with said main station and current supply mechanism arranged for normally causing suitable current flow in each of said circuits; telegraphic signaling means comprising, devices arranged for functional operation in response to cycles of change between predetermined limits in the intensity of current flow in one of said circuits thereat and mechanism for conditioning respective associated circuits to effect such cycles therein, said telegraphic signaling means including repeating mechanism at said main station responsive to such conditioning of certain of said circuits to cause corresponding conditioning of other of said circuits; and means for effecting telephonic communication over said circuits between said stations comprising, call manifesting mechanism arranged for functional response to cycles of change in the intensity of current flow in said respective circuits extending above the range of said first named cycles and during each of which cycles such intensity is reduced to less than a predetermined value, said manifesting mechanism including means at said main station for indicating circuits in which calls originate, telephone instruments at said main and sub-stations, means at said substations for operatively associating said instruments and circuits, and means at said main station whereby said instruments thereat may be operatively associated with either or both of any two of said circuits and whereby any two such circuits may be operatively associated with each other for telephonic communication therebetween, association of said telephone instruments with said circuits being so effected as to maintain conditions therein suited for complete intended functioning of said telegraphic signaling means and said call manifesting mechanism, and involving mechanism for so conditioning such circuits, respectively, as to effect such second named cycles therein.

6. In a combined telegraph and telephone signaling system having main and sub-stations and circuits each serially connecting a respective one or more of said sub-stations with said main station and current supply mechanism arranged for normally causing

- suitable current flow in each of said circuits;—telegraphic signaling means comprising,—devices arranged for functional operation in response to cycles of change in the intensity 5 of current flow in one of said circuits thereat each involving not less than a predetermined reduction in such intensity and mechanism for conditioning respective associated circuits to effect such cycles therein, said 10 telegraphic signaling means including repeating mechanism at said main station responsive to such conditioning of certain of said circuits to cause corresponding conditioning of other of said circuits; and means 15 for effecting telephonic communication over said circuits between said stations comprising,—call manifesting mechanism arranged for functional response to cycles of change each involving not less than a predetermined 20 reduction in the intensity of current flow in said respective circuits which last named reduction is less extensive than said first named reduction, said manifesting mechanism including means at said main station 25 for indicating circuits in which calls originate, telephone instruments at said main and sub-stations, means at said sub-stations for operatively associating said instruments and circuits, and means at said main station 30 whereby said instruments thereat may be operatively associated with either or both of any two of said circuits and whereby any two such circuits may be operatively associated with each other for telephonic communication 35 therebetween, association of said telephone instruments with said circuits being so effected as to maintain conditions therein suited for complete intended functioning of said telegraphic signaling means and said 40 call manifesting mechanism, and involving mechanism for so conditioning such circuits, respectively, as to effect such second named cycles therein.
7. In a combined telegraph and telephone 45 signaling system having main and sub-stations and circuits each serially connecting a respective one or more of said sub-stations with said main station and current supply mechanism arranged for normally causing 50 suitable current flow in each of said circuits;—telegraphic signaling means comprising,—code signaling mechanism adapted for conditioning associated circuits to effect cycles of change between predetermined limits in the intensity of current flow therein, repeating mechanism at said main station having electromagnetic mechanism arranged 55 for functional response to the aforesaid cycles of circuit condition and involving circuit controlling means arranged to formulate corresponding cycles in other of said circuits, manifesting means having electromagnetic mechanism arranged for functional response to such cycles of circuit condition, 60 and non-interference mechanism responsive 65 to the aforesaid cycles of circuit condition for controlling functional operation of said code signaling mechanism; and means for effecting telephonic communication over said circuits between said stations comprising,—call manifesting mechanism arranged for functional response to cycles of change in the intensity of current flow in said respective circuits extending above the range of said first named cycles and during each of which cycles such intensity is reduced to less than a predetermined value, telephone instruments at said stations together with means for operatively associating said instruments and circuits by so connecting respective ones of said instruments in shunt with windings of certain of said electromagnetic mechanisms as to maintain circuit conditions suited for complete 70 75 80 85 90 95 100 105 110 115 120 125 130
8. In a combined telegraph and telephone 95 signaling system having main and sub-stations and circuits each serially connecting a respective one or more of said sub-stations with said main station and current supply mechanism arranged for normally causing 100 suitable current flow in each of said circuits;—telegraphic signaling means comprising,—code signaling mechanism adapted for conditioning associated circuits to effect cycles of change between predetermined limits in the intensity of current flow therein, repeating mechanism at said main station having electromagnetic mechanism arranged 105 for functional response to the aforesaid cycles of circuit condition and involving circuit controlling means arranged to formulate corresponding cycles in other of said circuits, manifesting means having electromagnetic mechanism arranged for functional response to such cycles of circuit condition, and non-interference mechanism responsive 110 to the aforesaid cycles of circuit condition, and non-interference mechanism responsive to the aforesaid cycles of circuit condition for controlling functional operation of said code signaling mechanism; and means for effecting telephonic communication over said circuits between said stations comprising,—call manifesting mechanism arranged for functional response to cycles of change in the intensity of current flow in said respective circuits extending above the range of said first named cycles and during each of which cycles such intensity is reduced to less than a predetermined value, telephone instruments at said stations together with means for operatively associating said instruments and circuits by so connecting respective ones of said instruments in shunt with windings of certain of said electromagnetic mechanisms as to maintain circuit conditions suited for complete 115 120 125 130

intended functioning of said telegraphic signaling means, and involving mechanism for so conditioning such circuits, respectively, as to effect such second named cycles therein.

9. In a combined telegraph and telephone signaling system having main and sub-stations and circuits each serially connecting a respective one or more of said sub-stations with said main station and current supply mechanism arranged for normally causing suitable current flow in each of said circuits;—telegraphic signaling means comprising,—code signaling mechanism adapted for conditioning associated circuits to effect cycles of change between predetermined limits in the intensity of current flow therein, repeating mechanism at said main station having electromagnetic mechanism arranged for functional response to the aforesaid cycles of circuit condition and involving circuit controlling means arranged to formulate corresponding cycles in other of said circuits, manifesting means having electromagnetic mechanism arranged for functional response to such cycles of circuit condition, and non-interference mechanism responsive to the aforesaid cycles of circuit condition for controlling functional operation of said code signaling mechanism; and means for effecting telephonic communication over said circuits between said stations comprising,—call manifesting mechanism arranged for functional response to cycles of change each involving not less than a predetermined reduction in the intensity of current flow in said respective circuits which last named reduction is less extensive than said first named reduction, telephone instruments at said stations together with means for operatively associating said instruments and circuits by so connecting respective ones of said instruments in shunt with windings of certain of said electromagnetic mechanisms as to maintain circuit conditions suited for complete intended functioning of said telegraphic signaling means and said call manifesting mechanism, and involving mechanism for so conditioning such circuits, respectively, as to effect such second named cycles therein.
10. In a combined telegraph and telephone signaling system having main and sub-stations and circuits each serially connecting a respective one or more of said sub-stations with said main station and current supply mechanism arranged for normally causing suitable current flow in each of said circuits;—telegraphic signaling means comprising,—code signaling mechanism adapted for conditioning associated circuits to effect cycles of change each involving not less than a certain predetermined reduction in the intensity of current flow therein, repeating mechanism at said main station having electromagnetic mechanism arranged for functional response to the aforesaid cycles of circuit condition and involving circuit controlling means arranged to formulate corresponding cycles in other of said circuits, manifesting means having electromagnetic mechanism arranged for functional response to such cycles of circuit condition, and non-interference mechanism responsive to the aforesaid cycles of circuit condition for controlling functional operation of said code signaling mechanism; and means for effecting telephonic communication over said circuits between said stations comprising,—call manifesting mechanism arranged for functional response to cycles of change each involving not less than a predetermined reduction in the intensity of current flow in said respective circuits which last named reduction is less extensive than said first named reduction, telephone instruments at said stations together with means for opera-

trolling means arranged to formulate corresponding cycles in other of said circuits, manifesting means having electromagnetic mechanism arranged for functional response to such cycles of circuit condition, and non-interference mechanism responsive to the aforesaid cycles of circuit condition for controlling functional operation of said code signaling mechanism; and means for effecting telephonic communication over said circuits between said stations comprising,—call manifesting mechanism arranged for functional response to cycles of change each involving not less than a predetermined reduction in the intensity of current flow in said respective circuits which last named reduction is less extensive than said first named reduction, telephone instruments at said stations together with means for operatively associating said instruments and circuits by so connecting respective ones of said instruments in shunt with windings of certain of said electromagnetic mechanisms as to maintain circuit conditions suited for complete intended functioning of said telegraphic signaling means and said call manifesting mechanism, and involving mechanism for so conditioning such circuits, respectively, as to effect such second named cycles therein.

11. In a combined telegraph and telephone signaling system having main and sub-stations and circuits each serially connecting a respective one or more of said sub-stations with said main station and current supply mechanism arranged for normally causing suitable current flow in each of said circuits;—telegraphic signaling means comprising,—code signaling mechanism adapted for conditioning associated circuits to effect cycles of change each involving not less than a certain predetermined reduction in the intensity of current flow therein, repeating mechanism at said main station having electromagnetic mechanism arranged for functional response to the aforesaid cycles of circuit condition and involving circuit controlling means arranged to formulate corresponding cycles in other of said circuits, manifesting means having electromagnetic mechanism arranged for functional response to such cycles of circuit condition, and non-interference mechanism responsive to the aforesaid cycles of circuit condition for controlling functional operation of said code signaling mechanism; and means for effecting telephonic communication over said circuits between said stations comprising,—call manifesting mechanism arranged for functional response to cycles of change each involving not less than a predetermined reduction in the intensity of current flow in said respective circuits which last named reduction is less extensive than said first named reduction, telephone instruments at said stations together with means for opera-

tively associating said instruments and circuits by so connecting respective ones of said instruments in shunt with windings of certain of said electromagnetic mechanisms 5 as to maintain circuit conditions suited for complete intended functioning of said telegraphic signaling means, and involving mechanism for so conditioning such circuits, respectively, as to effect such second named 10 cycles therein.

12. In a combined telegraph and telephone signaling system having main and sub-stations and circuits each serially connecting a respective one or more of said sub-stations 15 with said main station and current supply mechanism arranged for normally causing suitable current flow in each of said circuits;—telegraphic signaling means comprising,—code signaling mechanism adapted for 20 conditioning associated circuits to effect cycles of change each involving not less than a certain predetermined reduction in the intensity of current flow therein, repeating mechanism at said main station having electromagnetic mechanism arranged for functional 25 response to the aforesaid cycles of circuit condition and involving circuit controlling means arranged to formulate corresponding cycles in other of said circuits, manifesting 30 means having electromagnetic mechanism arranged for functional response to such cycles of circuit condition, and non-interference mechanism responsive to the aforesaid cycles of circuit condition for controlling 35 functional operation of said code signaling mechanism; and means for effecting telephonic communication over said circuits between said stations comprising,—call manifesting mechanism arranged for 40 response to cycles of change each involving not less than a predetermined reduction in the intensity of current flow in said respective circuits which last named reduction is 45 less extensive than said first named reduction, telephone instruments at said stations together with means for operatively associating said instruments and circuits by connecting respective ones of said instruments in shunt with windings of certain of said 50 electromagnetic mechanisms, and involving mechanism for so conditioning such circuits, respectively, as to effect such second named 55 cycles therein.

13. In a combined telegraph and telephone signaling system having main and sub-stations and circuits each serially connecting a respective one or more of said sub-stations with said main station and current supply mechanism arranged for normally causing suitable current flow in each of said circuits;—telegraphic signaling means comprising,—code signaling mechanism adapted for 60 conditioning associated circuits to effect cycles of change between predetermined limits in the intensity of current flow 65

rent flow therein, repeating mechanism at said main station arranged for functional response to the aforesaid cycles of circuit condition and involving circuit controlling means arranged to formulate corresponding 70 cycles in other of said circuits, manifesting means arranged for functional response to such cycles of circuit condition, and non-interference mechanism responsive to the aforesaid cycles of circuit condition for controlling 75 functional operation of said code signaling mechanism; and means for effecting telephonic communication over said circuits between said stations comprising,—call manifesting mechanism arranged for 80 functional response to cycles of change in the intensity of current flow in said respective circuits extending above the range of said first named cycles and during each of which cycles such intensity is reduced to 85 less than a predetermined value, telephone instruments at said stations together with means for so operatively associating said instruments and circuits as to maintain circuit conditions suited for complete intended 90 functioning of said telegraphic signaling means and said call manifesting mechanism, and involving mechanism for so conditioning such circuits, respectively, as to effect such second named cycles therein. 95

14. In a combined telegraph and telephone signaling system having main and sub-stations and circuits each serially connecting a respective one or more of said sub-stations with said main station and current supply mechanism arranged for normally causing suitable current flow in each of said circuits;—telegraphic signaling means comprising,—code signaling mechanism adapted for conditioning associated 100 circuits to effect cycles of change between predetermined limits in the intensity of current flow therein, repeating mechanism at said main station arranged for functional response to the aforesaid cycles of circuit condition and involving circuit controlling 105 means arranged to formulate corresponding cycles in other of said circuits, manifesting means arranged for functional response to such cycles of circuit condition, and non-interference mechanism responsive to the aforesaid cycles of circuit condition for controlling functional operation of said code signaling mechanism; and means for effecting telephonic communication over said circuits between said stations comprising,—call manifesting mechanism arranged for functional response to cycles of change in the intensity of current flow in said respective circuits extending above the range of said first named cycles and during each of which cycles such intensity is reduced to less than a predetermined value, telephone instruments at said stations together with means for so operatively as- 110 115 120 125 130

sociating said instruments and circuits as to maintain circuit conditions suited for complete intended functioning of said telegraphic signaling means, and involving mechanism for so conditioning such circuits, respectively, as to effect such second named cycles therein.

15. In a combined telegraph and telephone signaling system having main and sub-stations and circuits each serially connecting a respective one or more of said sub-stations with said main station and current supply mechanism arranged for normally causing suitable current flow in each of said circuits;—telegraphic signaling means comprising,—code signaling mechanism adapted for conditioning associated circuits to effect cycles of change between predetermined limits in the intensity of current flow therein, repeating mechanism at said main station arranged for functional response to the aforesaid cycles of circuit condition and involving circuit controlling means arranged to formulate corresponding cycles in other of said circuits, manifesting means arranged for functional response to such cycles of circuit condition, and non-interference mechanism responsive to the aforesaid cycles of circuit condition for controlling functional operation of said code signaling mechanism; and means for effecting telephonic communication over said circuits between said stations comprising,—call manifesting mechanism arranged for functional response to cycles of change each involving not less than a predetermined reduction in the intensity of current flow in said respective circuits which last named reduction is less extensive than said first named reduction, telephone instruments at said stations together with means for so operatively associating said instruments and circuits as to maintain circuit conditions suited for complete intended functioning of said telegraphic signaling means and said call manifesting mechanism, and involving mechanism for so conditioning such circuits, respectively, as to effect such second named cycles therein.

16. In a combined telegraph and telephone signaling system having main and sub-stations and circuits each serially connecting a respective one or more of said sub-stations with said main station and current supply mechanism arranged for normally causing suitable current flow in each of said circuits;—telegraphic signaling means comprising,—code signaling mechanism adapted for conditioning associated circuits to effect cycles of change each involving not less than a certain predetermined reduction in the intensity of current flow therein, repeating mechanism at said main station arranged for functional response to the aforesaid cycles of circuit condition and involving circuit controlling means arranged to for-

mulate corresponding cycles in other of said circuits, manifesting means arranged for functional response to such cycles of circuit condition, and non-interference mechanism responsive to the aforesaid cycles of circuit condition for controlling functional operation of said code signaling mechanism; and means for effecting telephonic communication over said circuits between said stations comprising,—call manifesting mechanism arranged for functional response to cycles of change each involving not less than a predetermined reduction in the intensity of current flow in said respective circuits which last named reduction is less extensive than said first named reduction, telephone instruments at said stations together with means for so operatively associating said instruments and circuits as to maintain circuit conditions suited for complete intended functioning of said telegraphic signaling means and said call manifesting mechanism, and involving mechanism for so conditioning such circuits, respectively, as to effect such second named cycles therein.

17. In a combined telegraph and telephone signaling system having main and sub-stations and circuits each serially connecting a respective one or more of said sub-stations with said main station and current supply mechanism arranged for normally causing suitable current flow in each of said circuits;—telegraphic signaling means comprising,—code signaling mechanism adapted for conditioning associated circuits to effect cycles of change each involving not less than a certain predetermined reduction in the intensity of current flow therein, repeating mechanism at said main station arranged for functional response to the aforesaid cycles of circuit condition and involving circuit controlling means arranged to formulate corresponding cycles in other of said circuits, manifesting means arranged for functional response to such cycles of circuit condition, and non-interference mechanism responsive to the aforesaid cycles of circuit condition for controlling functional operation of said code signaling mechanism; and means for effecting telephonic communication over said circuits between said stations comprising,—call manifesting mechanism arranged for functional response to cycles of change each involving not less than a certain predetermined reduction in the intensity of current flow in said respective circuits which last named reduction is less extensive than said first named reduction, telephone instruments at said stations together with means for so operatively associating said instruments and circuits as to maintain circuit conditions suited for complete intended functioning of said telegraphic signaling means and said call manifesting mechanism, and involving mechanism for so conditioning such circuits, respectively, as to effect such second named cycles therein.

18. In a combined telegraph and telephone signaling system having main and sub-stations and circuits each serially connecting a respective one or more of said sub-stations with said main station and current supply mechanism arranged for normally causing suitable current flow in each of said circuits;—telegraphic signaling means comprising,—code signaling mechanism adapted for conditioning associated circuits to effect cycles of change each involving not less than a certain predetermined reduction in the intensity of current flow in said respective circuits which last named reduction is less extensive than said first named reduction, telephone instruments at said stations together with means for so operatively associating said instruments and circuits as to maintain circuit conditions suited for complete intended functioning of said telegraphic signaling means and in-

volving mechanism for so conditioning such circuits, respectively, as to effect such second named cycles therein.

18. In a combined telegraph and telephone signaling system having main and sub-stations and circuits each serially connecting a respective one or more of said sub-stations with said main station and current supply mechanism arranged for normally causing suitable current flow in each of said circuits;—telegraphic signaling means comprising,—code signaling mechanism adapted for conditioning associated circuits to effect cycles of change each involving not less than a certain predetermined reduction in the intensity of current flow therein, repeating mechanism at said main station arranged for functional response to the aforesaid cycles of circuit condition and involving circuit controlling means arranged to formulate corresponding cycles in other of said circuits, manifesting means arranged for functional response to such cycles of circuit condition, and non-interference mechanism responsive to the aforesaid cycles of circuit condition for controlling functional operation of said code signaling mechanism; and means for effecting telephonic communication over said circuits between said stations comprising,—call manifesting mechanism arranged for functional response to cycles of change each involving not less than a predetermined reduction in the intensity of current flow in said respective circuits which last named reduction is less extensive than said first named reduction, telephone instruments at said stations together with means for operatively associating said instruments and circuits, and involving mechanism for so conditioning such circuits, respectively, as to effect such second named cycles therein.

19. In a combined telegraph and telephone signaling system having main and sub-stations and circuits each connecting a respective one or more of said sub-stations with said main station and current supply mechanism arranged for normally causing suitable current flow in each of said circuits;—telegraphic signaling means comprising,—devices having electromagnetic mechanism arranged for functional operation in response to cycles of change between predetermined limits in the intensity of current flow in one of said circuits thereat and mechanism for conditioning respective associated circuits to effect such cycles therein, said telegraphic signaling means including repeating mechanism at said main station responsive to such conditioning of certain of said circuits to cause corresponding conditioning of other of said circuits; and means for effecting telephonic communication over said circuits between said stations comprising,—call manifesting mechanism arranged for functional response

to cycles of change in the intensity of current flow in said respective circuits extending above the range of said first named cycles and during each of which cycles such intensity is reduced to less than a predetermined value, telephone instruments at said stations together with means for operatively associating said instruments and circuits by so connecting respective ones of said instruments in shunt with windings of certain of said electromagnetic mechanisms as to maintain circuit conditions suited for complete intended functioning of said telegraphic signaling means and said call manifesting mechanism, and involving mechanism for so conditioning such circuits, respectively, as to effect such second named cycles therein.

20. In a combined telegraph and telephone signaling system having main and sub-stations and circuits each connecting a respective one or more of said sub-stations with said main station and current supply mechanism arranged for normally causing suitable current flow in each of said circuits;—telegraphic signaling means comprising,—devices having electromagnetic mechanism arranged for functional operation in response to cycles of change between predetermined limits in the intensity of current flow in one of said circuits thereat and mechanism for conditioning respective associated circuits to effect such cycles therein, said telegraphic signaling means including repeating mechanism at said main station responsive to such conditioning of certain of said circuits to cause corresponding conditioning of other of said circuits; and means for effecting telephonic communication over said circuits between said stations comprising,—call manifesting mechanism arranged for functional response to cycles of change in the intensity of current flow in said respective circuits extending above the range of said first named cycles and during each of which cycles such intensity is reduced to less than a predetermined value, telephone instruments at said stations together with means for operatively associating said instruments and circuits by so connecting respective ones of said instruments in shunt with windings of certain of said electromagnetic mechanisms as to maintain circuit conditions suited for complete intended functioning of said telegraphic signaling means and involving mechanism for so conditioning such circuits, respectively, as to effect such second named cycles therein.

21. In a combined telegraph and telephone signaling system having main and sub-stations and circuits each connecting a respective one or more of said sub-stations with said main station and current supply mechanism arranged for normally causing suitable current flow in each of said circuits;—

- telegraphic signaling means comprising,— devices having electromagnetic mechanism arranged for functional operation in response to cycles of change between predetermined limits in the intensity of current flow in one of said circuits thereat and mechanism for conditioning respective associated circuits to effect such cycles therein, said telegraphic signaling means including repeating mechanism at said main station responsive to such conditioning of certain of said circuits to cause corresponding conditioning of other of said circuits; and means for effecting telephonic communication over said circuits between said stations comprising,— call manifesting mechanism arranged for functional response to cycles of change in the intensity of current flow in said respective circuits extending above the range of said first named cycles and during each of which cycles such intensity is reduced to less than a predetermined value, telephone instruments at said stations together with means for operatively associating said instruments and circuits by connecting respective ones of said instruments in shunt with windings of certain of said electromagnetic mechanisms, and involving mechanism for so conditioning such circuits, respectively, as to effect such second named cycles therein.
22. In a combined telegraph and telephone signaling system having main and sub-stations and circuits each connecting a respective one or more of said sub-stations with said main station and current supply mechanism arranged for normally causing suitable current flow in each of said circuits;—telegraphic signaling means comprising,—devices having electro-magnetic mechanism arranged for functional operation in response to cycles of change in the intensity of current flow in one of said circuits thereat each involving not less than a predetermined reduction in such intensity and mechanism for conditioning respective associated circuits to effect such cycles therein, said telegraphic signaling means including repeating mechanism at said main station responsive to such conditioning of certain of said circuits to cause corresponding conditioning of other of said circuits; and means for effecting telephonic communication over said circuits between said stations comprising,—call manifesting mechanism arranged for functional response to cycles of change each involving not less than a predetermined reduction in the intensity of current flow in said respective circuits which last named reduction is less extensive than said first named reduction, telephone instruments at said stations together with means for operatively associating said instruments and circuits by so connecting respective ones of said instruments in shunt with windings of certain of said electromagnetic mechanisms as to maintain circuit conditions suited for complete intended functioning of said telegraphic signaling means, and involving mechanism for so conditioning such circuits, respectively, as to effect such second named cycles therein.
24. In a combined telegraph and telephone signaling system having main and sub-stations and circuits each connecting a respective one or more of said sub-stations with said main station and current supply mechanism arranged for normally causing suitable current flow in each of said circuits;—telegraphic signaling means comprising,—devices having electro-magnetic mechanism arranged for functional operation in response to cycles of change in the intensity of current flow in one of said circuits thereat each involving not less than a predetermined reduction in such intensity and mechanism for conditioning respective associated circuits to effect such cycles
- electromagnetic mechanisms as to maintain circuit conditions suited for complete intended functioning of said telegraphic signaling means and said call manifesting mechanism, and involving mechanism for so conditioning such circuits, respectively, as to effect such second named cycles therein.
23. In a combined telegraph and telephone signaling system having main and sub-stations and circuits each connecting a respective one or more of said sub-stations with said main station and current supply mechanism arranged for normally causing suitable current flow in each of said circuits;—telegraphic signaling means comprising,—devices having electro-magnetic mechanism arranged for functional operation in response to cycles of change in the intensity of current flow in one of said circuits thereat each involving not less than a predetermined reduction in such intensity and mechanism for conditioning respective associated circuits to effect such cycles therein, said telegraphic signaling means including repeating mechanism at said main station responsive to such conditioning of certain of said circuits to cause corresponding conditioning of other of said circuits; and means for effecting telephonic communication over said circuits between said stations comprising,—call manifesting mechanism arranged for functional response to cycles of change each involving not less than a predetermined reduction in the intensity of current flow in said respective circuits which last named reduction is less extensive than said first named reduction, telephone instruments at said stations together with means for operatively associating said instruments and circuits by so connecting respective ones of said instruments in shunt with windings of certain of said electromagnetic mechanisms as to maintain circuit conditions suited for complete intended functioning of said telegraphic signaling means, and involving mechanism for so conditioning such circuits, respectively, as to effect such second named cycles therein.
25. In a combined telegraph and telephone signaling system having main and sub-stations and circuits each connecting a respective one or more of said sub-stations with said main station and current supply mechanism arranged for normally causing suitable current flow in each of said circuits;—telegraphic signaling means comprising,—devices having electro-magnetic mechanism arranged for functional response to cycles of change each involving not less than a predetermined reduction in the intensity of current flow in one of said circuits thereat each involving not less than a predetermined reduction in such intensity and mechanism for conditioning respective associated circuits to effect such cycles therein, said telegraphic signaling means including repeating mechanism at said main station responsive to such conditioning of certain of said circuits to cause corresponding conditioning of other of said circuits; and means for effecting telephonic communication over said circuits between said stations comprising,—call manifesting mechanism arranged for functional response to cycles of change each involving not less than a predetermined reduction in the intensity of current flow in said respective circuits which last named reduction is less extensive than said first named reduction, telephone instruments at said stations together with means for operatively associating said instruments and circuits by so connecting respective ones of said instruments in shunt with windings of certain of said electromagnetic mechanisms as to maintain circuit conditions suited for complete intended functioning of said telegraphic signaling means, and involving mechanism for so conditioning such circuits, respectively, as to effect such second named cycles therein.
26. In a combined telegraph and telephone signaling system having main and sub-stations and circuits each connecting a respective one or more of said sub-stations with said main station and current supply mechanism arranged for normally causing suitable current flow in each of said circuits;—telegraphic signaling means comprising,—devices having electro-magnetic mechanism arranged for functional operation in response to cycles of change in the intensity of current flow in one of said circuits thereat each involving not less than a predetermined reduction in such intensity and mechanism for conditioning respective associated circuits to effect such cycles

therein, said telegraphic signaling means including repeating mechanism at said main station responsive to such conditioning of certain of said circuits to cause corresponding conditioning of other of said circuits; and means for effecting telephonic communication over said circuits between said stations comprising,—call manifesting mechanism arranged for functional response to 5 cycles of change each involving not less than a predetermined reduction in the intensity of current flow in said respective circuits which last named reduction is less extensive than said first named reduction, telephone instruments at said stations together with means for operatively associating said instruments and circuits by connecting respective ones of said instruments in shunt with windings of certain of said electro- 10 magnetic mechanisms, and involving mechanism for so conditioning such circuits, respectively, as to effect such second named cycles therein.

25. In a combined telegraph and telephone signaling system having main and sub-stations and circuits each connecting a respective one or more of said sub-stations with said main station and current supply mechanism arranged for normally causing suitable current flow in each of said circuits;—telegraphic signaling means comprising,—devices arranged for functional operation in response to cycles of change between predetermined limits in the intensity of current 30 flow in one of said circuits thereat and mechanism for conditioning respective associated circuits to effect such cycles therein, said telegraphic signaling means including repeating mechanism at said main station 35 responsive to such conditioning of certain of said circuits to cause corresponding conditioning of other of said circuits; and means for effecting telephonic communication over said circuits between stations comprising,—call manifesting mechanism arranged for functional response to cycles of change in the intensity of current flow in said respective circuits extending above the range of said first named cycles and during each of which 40 cycles such intensity is reduced to less than a predetermined value, telephone instruments at said stations together with means for so operatively associating said instruments and circuits as to maintain circuit 45 conditions suited for complete intended functioning of said telegraphic signaling means and said call manifesting mechanism, and involving mechanism for so conditioning such circuits, respectively, as to effect such second named cycles therein.

26. In a combined telegraph and telephone signaling system having main and sub-stations and circuits each connecting a respective one or more of said sub-stations with

said main station and current supply mechanism arranged for normally causing suitable current flow in each of said circuits;—telegraphic signaling means comprising,—devices arranged for functional operation in response to cycles of change between predetermined limits in the intensity of current flow in one of said circuits thereat and mechanism for conditioning respective associated circuits to effect such cycles therein, said telegraphic signaling means including repeating mechanism at said main station responsive to such conditioning of certain of said circuits to cause corresponding conditioning of other of said circuits; and means for effecting telephonic communication over said circuits between stations comprising,—call manifesting mechanism arranged for functional response to cycles of change in the intensity of current flow in said respective circuits extending above the range of said first named cycles and during each of which cycles such intensity is reduced to less than a predetermined value, telephone instruments at said stations together with means for so operatively associating said instruments and circuits as to maintain circuit conditions suited for complete intended functioning of said telegraphic signaling means, and involving mechanism for so conditioning such circuits, respectively, as to effect such second named cycles therein.

27. In a combined telegraph and telephone signaling system having main and sub-stations and circuits each connecting a respective one or more of said sub-stations with said main station and current supply mechanism arranged for normally causing suitable current flow in each of said circuits;—telegraphic signaling means comprising,—devices arranged for functional operation in response to cycles of change between predetermined limits in the intensity of current flow in one of said circuits thereat and mechanism for conditioning respective associated circuits to effect such cycles therein, said telegraphic signaling means including repeating mechanism at said main station responsive to such conditioning of certain of said circuits to cause corresponding conditioning of other of said circuits; and means for effecting telephonic communication over said circuits between stations comprising,—call manifesting mechanism arranged for functional response to cycles of change in the intensity of current flow in said respective circuits extending above the range of said first named cycles and during each of which cycles such intensity is reduced to less than a predetermined value, telephone instruments at said stations together with means for operatively associating said instruments and circuits, and in-

volving mechanism for so conditioning such circuits, respectively, as to effect such second named cycles therein.

28. In a combined telegraph and telephone signaling system having main and sub-stations and circuits each connecting a respective one or more of said sub-stations with said main station and current supply mechanism arranged for normally causing suitable current flow in each of said circuits;—telegraphic signaling means comprising,—devices arranged for functional operation in response to cycles of change in the intensity of current flow in one of said circuits thereat each involving not less than a predetermined reduction in such intensity and mechanism for conditioning respective associated circuits to effect such cycles therein, said telegraphic signaling means including repeating mechanism at said main station responsive to such conditioning of certain of said circuits to cause corresponding conditioning of other of said circuits; and means for effecting telephonic communication over said circuits between said stations comprising,—call manifesting mechanism arranged for functional response to cycles of change each involving not less than a predetermined reduction in the intensity of current flow in said respective circuits which last named reduction is less extensive than said first named reduction, telephone instruments at said stations together with means for so operatively associating said instruments and circuits as to maintain circuit conditions suited for complete intended functioning of said telegraphic signaling means, and involving mechanism for so conditioning such circuits, respectively, as to effect such second named cycles therein.

29. In a combined telegraph and telephone signaling system having main and sub-stations and circuits each connecting a respective one or more of said sub-stations with said main station and current supply mechanism arranged for normally causing suitable current flow in each of said circuits;—telegraphic signaling means comprising;—devices arranged for functional operation in response to cycles of change in the intensity of current flow in one of said circuits thereat each involving not less than a predetermined reduction in such intensity and mechanism for conditioning respective associated circuits to effect such cycles therein, said telegraphic signaling means including repeating mechanism at said main station responsive to such conditioning of certain of said circuits to cause corresponding conditioning of other of said circuits; and means for effecting telephonic communication over said circuits between said stations comprising,—call manifesting mechanism arranged for functional response to cycles

of change each involving not less than a predetermined reduction in the intensity of current flow in said respective circuits which last named reduction is less extensive than said first named reduction, telephone instruments at said stations together with means for so operatively associating said instruments and circuits as to maintain circuit conditions suited for complete intended functioning of said telegraphic signaling means, and involving mechanism for so conditioning such circuits, respectively, as to effect such second named cycles therein.

30. In a combined telegraph and telephone signaling system having main and sub-stations and circuits each connecting a respective one or more of said sub-stations with said main station and current supply mechanism arranged for normally causing suitable current flow in each of said circuits;—telegraphic signaling means comprising,—devices arranged for functional operation in response to cycles of change in the intensity of current flow in one of said circuits thereat each involving not less than a predetermined reduction in such intensity and mechanism for conditioning respective associated circuits to effect such cycles therein, said telegraphic signaling means including repeating mechanism at said main station responsive to such conditioning of certain of said circuits to cause corresponding conditioning of other of said circuits; and means for effecting telephonic communication over said circuits between said stations comprising,—call manifesting mechanism arranged for functional response to cycles of change each involving not less than a predetermined reduction in the intensity of current flow in said respective circuits which last named reduction is less extensive than said first named reduction, telephone instruments at said stations together with means for operatively associating said instruments and circuits, and involving mechanism for so conditioning such circuits, respectively, as to effect such second named cycles therein.

31. In a combined telegraph and telephone signaling system having main and sub-stations and circuits each serially connecting a respective one or more of said sub-stations with said main station and current supply mechanism arranged for normally causing suitable current flow in each of said circuits;—telegraphic signaling means comprising—devices having electromagnetic mechanism arranged for functional operation in response to cycles of change between predetermined limits in the intensity of current flow in one of said circuits thereat and mechanism for conditioning respective associated circuits to effect such cycles therein, said telegraphic signaling means including repeating mechanism at said main sta-

- tion responsive to such conditioning of certain of said circuits to cause corresponding conditioning of other of said circuits; and means for effecting telephonic communication over circuits between said stations comprising,—call manifesting mechanism arranged for functional response to cycles of change in the intensity of current flow in said respective circuits extending above the 5 range of said first named cycles and during each of which cycles such intensity is reduced to less than a predetermined value, said manifesting mechanism including means at said main station for indicating circuits 10 in which calls originate and responsive devices each having an electromagnet winding serially included in its associated circuit at each of certain of said sub-stations, respectively, telephone instruments at said main 15 and sub-stations, said instruments at certain of said sub-stations including a receiver arranged to be connected in parallel with said electromagnet winding of said responsive device thereat and a transmitter shunted 20 by a resistance serially included in its associated circuit and also normally shunted by a current path of comparatively low resistance, means at each of said certain sub-stations for so connecting said receiver in 25 parallel with said winding and for breaking said shunt path around said transmitter, and means at said main station whereby said instruments thereat may be operatively associated with either or both of any two of 30 said circuits and whereby any two such circuits may be operatively associated with each other for telephonic communication therebetween without altering the functional relationship of such circuits as to telegraphic 35 signals, association of said telephone instruments with said circuits being effected by so connecting respective ones of said instruments in shunt with windings of certain of said electromagnetic mechanisms as to 40 maintain circuit conditions suited for complete intended functioning of said telegraphic signaling means and said call manifesting mechanism, and involving mechanism for so conditioning such circuits, respectively, as to 45 effect such second named cycles therein. 50
32. In a combined telegraph and telephone signaling system having main and sub-stations and circuits each serially connecting a respective one or more of said sub-stations 55 with said main station and current supply mechanism arranged for normally causing suitable current flow in each of said circuits;—telegraphic signaling means comprising,—devices having electromagnetic mechanism arranged for functional operation in response to cycles of change in the intensity of current flow in one of said circuits thereat each involving not less than a predetermined reduction in such intensity and mechanism 60 for conditioning respective associated circuits to effect such cycles therein, said telegraphic signaling means including repeating mechanism at said main station responsive to such conditioning of certain of said circuits to cause corresponding conditioning of other 65 of said circuits; and means for effecting telephonic communication over said circuits between said stations comprising,—call manifesting mechanism arranged for functional response to cycles of change each involving not less than a predetermined reduction in the intensity of current flow in said respective circuits which last named reduction is less extensive than said first named reduction, said manifesting mechanism including means at said main station for indicating circuits 70 in which calls originate and responsive devices each having an electromagnet winding serially included in its associated circuit at each of certain of said sub-stations, respectively, telephone instruments at said main and sub-stations, said instruments at certain of said sub-stations including a receiver arranged to be connected in parallel with said electromagnet winding of said responsive device thereat and a transmitter shunted by a resistance serially included in its associated circuit and also normally shunted by a current path of comparatively 75 low resistance, means at each of said certain sub-stations for so connecting said receiver in parallel with said winding and for breaking said shunt path around said transmitter, and means at said main station whereby said instruments thereat may be operatively associated with either or both of any two of said circuits and whereby any two such circuits may be operatively associated with each other for telephonic communication therebetween without altering the functional relationship of such circuits as to 80 telegraphic signals, association of said telephone instruments with said circuits being effected by so connecting respective ones of said instruments in shunt with windings of certain of said electromagnetic mechanisms as to maintain circuit conditions suited for complete intended functioning of said telegraphic signaling means and said call manifesting mechanism, and involving mechanism for so conditioning such circuits, respectively, as to effect such second named cycles therein. 85
33. In a combined telegraph and telephone signaling system having main and sub-stations and circuits each serially connecting a respective one or more of said sub-stations with said main station and current supply mechanism arranged for normally causing suitable current flow in each of said circuits;—telegraphic signaling means comprising,—devices arranged for functional operation in response to cycles of change between predetermined limits in the intensity of current flow in one of said circuits there- 90 95 100 105 110 115 120 125 130

at and mechanism for conditioning respective associated circuits to effect such cycles therein, said telegraphic signaling means including repeating mechanism at said main station responsive to such conditioning of certain of said circuits to cause corresponding conditioning of other of said circuits; and means for effecting telephonic communication over said circuits between said stations comprising,—call manifesting mechanism arranged for functional response to cycles of change in the intensity of current flow in said respective circuits extending above the range of said first named cycles and during each of which cycles such intensity is reduced to less than a predetermined value, said manifesting mechanism including means at said main station for indicating circuits in which calls originate, telephone instruments at said main and sub-stations, said instruments at certain of said sub-stations including a transmitter shunted by a resistance serially included in its associated circuit and also normally shunted by a current path of comparatively low resistance, means at each of said certain sub-stations for breaking said shunt path around said transmitter, and means at said main station whereby said instruments thereat may be operatively associated with either or both of any two of said circuits and whereby any two such circuits may be operatively associated with each other for telephonic communication therebetween without altering the functional relationship of such circuits as to telegraphic signals, association of said telephone instruments with said circuits being so effected as to maintain conditions therein suited for complete intended functioning of said telegraphic signaling means and said call manifesting mechanism, and involving mechanism for so conditioning such circuits, respectively, as to effect such second named cycles therein.

34. In a combined telegraph and telephone signaling system having main and sub-stations and circuits each serially connecting a respective one or more of said sub-stations with said main station and current supply mechanism arranged for normally causing suitable current flow in each of said circuits;—telegraphic signaling means com-

prising,—devices arranged for functional operation in response to cycles of change in the intensity of current flow in one of said circuits thereat each involving not less than a predetermined reduction in such intensity and mechanism for conditioning respective associated circuits to effect such cycles therein, said telegraphic signaling means including repeating mechanism at said main station responsive to such conditioning of certain of said circuits to cause corresponding conditioning of other of said circuits; and means for effecting telephonic communication over said circuits between said stations comprising,—call manifesting mechanism arranged for functional response to cycles of change each involving not less than a predetermined reduction in the intensity of current flow in said respective circuits which last named reduction is less extensive than said first named reduction, said manifesting mechanism including means at said main station for indicating circuits in which calls originate, telephone instruments at said main and sub-stations, said instruments at certain of said sub-stations including a transmitter shunted by a resistance serially included in its associated circuit and also normally shunted by a current path of comparatively low resistance, means at each of said certain sub-stations for breaking said shunt path around said transmitter, and means at said main station whereby said instruments thereat may be operatively associated with either or both of any two of said circuits and whereby any two such circuits may be operatively associated with each other for telephonic communication therebetween without altering the functional relationship of such circuits as to telegraphic signals, association of said telephone instruments with said circuits being so effected as to maintain conditions therein suited for complete intended functioning of said telegraphic signaling means and said call manifesting mechanism, and involving mechanism for so conditioning such circuits, respectively, as to effect such second named cycles therein.

In witness whereof, I hereunto subscribe my name, this 18th day of November, 1924.

FREDERICK B. PHILBRICK.
